(57) **CLAIM**

The ornamental design for a faceplate groove for a golf club, as shown and described.

DESCRIPTION

FIG. 1 is a perspective view showing the faceplate groove for a golf club, the dotted line depiction of a golf club head being for illustrative purposes only and forming no part of the claimed design;

FIG. 2 is an enlarged vertical sectional view taken generally on the line 2—2 of FIG. 1;

FIG. 3 is a perspective view showing the faceplate groove for a golf club, in accordance with an alternative preferred form of the invention, the dotted line depiction of a fragmented golf club being for illustrative purposes only and forming no part of the claimed design; and,

FIG. 4 is an enlarged vertical sectional view taken generally on the line 4—4 of FIG. 2;
